ELECTRORESPONSIVE APPARATUS

Filed April 7, 1923.

UNITED STATES PATENT OFFICE.

HOWARD A. THOMPSON, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRORESPONSIVE APPARATUS.

Application filed April 7, 1923. Serial No. 630,510.

My invention relates to electro-responsive apparatus, and particularly to apparatus adapted for intermittent operation. Apparatus embodying my invention is particularly well suited for, though in no way limited to, the operation of highway crossing signals of the wig-wag type.

I will describe a few forms of apparatus embodying my invention, and will then 10 point out the novel features thereof in claims.

In the accompanying drawing Fig. 1 is a diagrammatic view showing one form of apparatus embodying my invention. Figs. 2 15 and 3 are views showing modifications of the apparatus shown in Fig. 1 and also embodying my invention.

Referring first to Fig. 1, the reference characters 1 and 1^a designate the track rails 20 of a railway over which traffic normally moves in the direction of the arrow, and which railway is intersected by a highway C. Extending to the left from the highway C is a track section A—B which is separated 25 from the remainder of the track by insulated joints 2. This section is provided with a track relay R connected across the rails adjacent the intersection of highway C and the section A—B. This section is also provided 30 with a source of track circuit current comprising, as shown in the drawing, a secondary winding 31 of a transformer T, whose primary 32 is constantly supplied with alternating current from line wires 3 fed by a 35 generator M. The signal is mounted in some exposed place near the grade crossing and comprises a banner H having an arm 26 pivotally mounted at point 33 and carrying a conspicuous emblem such as a disk 27 bearing a warning such as the legend Stop. The 40 armature 29 of a tractive magnet G is mechanically connected to the banner H in such a manner that when magnet G is energized, armature 29 is drawn upwards and banner 45 H is swung to the right and is restrained in such a position that disk 27 is concealed by a shield 30. Interposed between armature 29 and banner H is a resilient member, preferably in the form of a coil spring 28. The 50 magnet G is provided with a circuit which passes from a source of energy as a second-

ary 5 of transformer D through wire 18, front contact 6—7 of relay R, wire 17, winding 16 of magnet G, wires 15, 13, and 12, back to secondary 5 of transformer D. This 55 circuit is closed only when relay R is energized, in which case banner H is concealed from view. The primary 4 of transformer D is constantly supplied with alternating current from line wires 3. 60

When section A—B is occupied by a train, relay R is de-energized thus opening front contact 6—7 and de-energizing magnet G. At the same time banner H is caused to 65 oscillate by the apparatus which I will now describe.

The reference character F designates an electro-magnetic device comprising a core F² provided with a winding 20, two legs F³, and an armature F' which armature is located between the legs F³ and in operative relation with respect to the core F². This armature F' is biased by some means such as gravity to a position wherein it is spaced from the core F². When winding 20 is energized, armature F' is picked up or drawn toward the core F², thus completing the magnetic circuit. Spacing pins 21 may be inserted in the face of core 21 to prevent the actual contact of armature F' and core F², 70 thus eliminating the possibility of sticking of the armature due to residual magnetism. The armature F' is mechanically connected to the banner H by means of a bell crank 22 pivoted at point 23 and so disposed that 75 alternate raising and lowering of this armature will produce oscillations in the banner about its pivot 23. A resilient spring 25 is inserted between the bell crank 24 and armature F'. Since the reluctance of the magnetic circuit of device F is considerably less 80 when the armature F' is in its upper position than when in its lower position, it follows that the reactance of the coil 20 is considerably greater when armature F' is in 85 its upper position than when in its lower position. The energization of coil 20 is controlled by means of a thermo-sensitive cell E having a heating element 9 and an element 10 of thermo-sensitive material, that is, material which has the property of varying its 90 electrical characteristics in response to 100

changes in temperature. These two elements are in mutual electrical contact and are so associated that the thermo-sensitive element 10 is subjected to variations in temperature 5 of the heating element due to the presence and absence of current in this heating element. This cell E is provided with a heating circuit which passes from secondary 5 of transformer D through wire 18, back contact 6-8 of relay R, heating element 9, non-inductive resistance 11, and wire 12 back to secondary 5 of transformer D. This circuit is closed only when relay R is de-energized. The thermo-sensitive cell E is provided with 15 another circuit which passes from secondary 5 of transformer D, through wire 18, contact 6-8 of relay R, heating element 9 and thermo-sensitive element 10 of thermo-sensitive cell E, wire 19, winding 20 of device F, and wires 14, 13 and 12 back to secondary 5 of transformer D. This circuit is closed only when relay R is de-energized.

Assuming that relay R is open, so that the banner H is released, the operation of device F is as follows: As soon as the circuit for heating element 9 of thermo-sensitive cell E is closed at contact 6-8, current flows through this element thus generating heat which is transmitted to thermo-sensitive element 10. The consequent increase in the temperature of this thermo-sensitive element decreases its resistance and allows a small amount of current to flow through it. This current is not sufficient to pick up the armature F' but it is sufficient to further increase the temperature of element 10 with a resulting further decrease in the resistance of this element. This action is accumulative and continues until the current through thermo-sensitive element 10 and winding 20 is enough to pick up armature F', thus swinging banner H to the left. Now when the armature F' moves to its upper position, the reactance of the winding 20, and hence the 45 total impedance of the circuit of which the winding 20 is a part, is considerably increased. The resulting decrease in the current through the thermo-sensitive element 10 decreases the temperature of this element 50 which increases its resistance and further reduces the current through the element. This action is also accumulative and continues till the current is reduced to such a low value that it is no longer sufficient to 55 hold armature F' in its upper position. The armature thereupon returns to its lower position. This cycle is repeated as long as relay R is de-energized.

The voltage available for operating device F may be varied by variation in the value of resistance 11 which is connected in series with heating element 9 of thermo-sensitive cell E and in parallel with winding 20 of device F. The time interval between successive movements of armature F'

may be regulated by proper design and proportioning of device F and thermo-sensitive cell E.

The operation of the entire apparatus is as follows:

When section A-B is unoccupied, relay R is energized and magnet G, also being energized, holds banner H behind the shield 30. Now if a train enters section A-B, relay R becomes de-energized, and this in turn de-energizes magnet G so that armature 29 releases the banner H. The opening of relay R also energizes thermo-sensitive cell E which then causes armature F' of device F to move up and down thus causing banner H to oscillate or "wag" back and forth on its axis 33 as hereinbefore explained. This action continues until the train leaves the section A-B whereupon relay R will be energized, and the consequent energization of magnet G restores the apparatus to normal.

Referring now to Figs. 2 and 3, the change in the total impedance of the circuit which includes winding 20 of device F resulting from the change in the reactance of winding 20 due to the pick-up of armature 29 may be accentuated by introducing a capacity in this circuit. In order to obtain a large capacity from a condenser of reasonable size a step-up transformer S may be used to increase the voltage available at the terminals of the condenser W. The transformer may be connected in parallel with winding 20 as shown in Fig. 2, or in series with winding 20 as shown in Fig. 3. With the parallel connection shown in Fig. 2, the condenser is in resonance with winding 20 when plunger F' is closed against core F², whereas with the series connection shown in Fig. 3 the condenser is in resonance with winding 20 when the plunger F' has dropped away from the core.

Although I have herein shown and described only a few forms of apparatus embodying my invention it is understood that various changes and modifications may be made therein within the scope of the appended claims, without departing from the spirit and scope of my invention.

Having thus described my invention, what I claim is:

1. In combination, an electric conductor, a device controlled by the flow of current in said conductor and operating when such current exceeds a given value to increase the impedance of said conductor thereby decreasing the value of the current, and means included in circuit with said conductor and responsive to a decrease in said current for further decreasing this current to a value below said given value.

2. In combination, a magnet winding, a device controlled by said magnet winding and operating when the flow of current in

said winding exceeds a given value to increase the reactance of said winding thereby decreasing the value of the current, and means included in circuit with said conductor and responsive to a decrease in said current for further decreasing this current to a value below said given value.

3. In combination, a magnet having a core provided with a winding having an electric current flowing at times therein, an armature controlled by said magnet and operating when said current exceeds a given value to decrease the reluctance of said core thus increasing the reactance of said winding and thereby decreasing the value of the current, and means included in circuit with said conductor and responsive to a decrease in said current for further decreasing this current to a value below said given value.

20 4. In combination, an electric conductor, a device controlled by the flow of current in said conductor and operating when such cur-

rent exceeds a given value to increase the impedance of said conductor thereby decreasing the value of the current, means for 25 accentuating such impedance change, an element included in circuit with said conductor having a high negative temperature coefficient, and means for varying the temperature of said element.

5. In combination, an electric conductor, a device controlled by the flow of current in said conductor and operating when such current exceeds a given value to increase the impedance of said conductor thereby decreasing the value of the current, a capacity connected in parallel with said device, an element included in circuit with said conductor having a high negative temperature coefficient, and means for varying the temperature of said element.

30 35 40 In testimony whereof I affix my signature.

HOWARD A. THOMPSON.
